CARBON PAPER HOLDER FOR MANIFOLD-
ING TYPEWRITERS

Joseph Carroll Doyle, Baltimore, Md., assignor to
Kee Lox Manufacturing Company, Rochester,
N. Y., a corporation of New York

Application November 28, 1945, Serial No. 631,375

12 Claims. (Cl. 197—126)

1

This invention relates to carbon paper holding means for manifolding typewriters of the type in which a series of sheets of carbon paper are each connected to an independent supporting bar or blade of a movable carbon paper carriage and interposed between continuous sheets of paper on which the desired typewritten records are to be made, the carbon paper carriage being withdrawn after each typing operation to remove the carbon sheets from between and permit tearing off the typewritten records from the continuous record sheets, and it has for its principal purpose to afford a structure including a holding or leader sheet that can be permanently fastened to a supporting bar of a typewriter and a carbon paper carrier that is removably associated with the holding sheet whereby the carbon paper can be adjusted or renewed by detaching its carrier from the holding sheet, without the necessity of removing the holding sheet, or otherwise disturbing the relation between the holding sheet and the typewriter supporting bar.

Another purpose of the invention is to afford a construction of holding sheet that is permanently secured to a supporting bar and permits the use of a continuous sheet of carbon paper wound or rolled on a carrier, which can be quickly removed from and reattached to the permanent holding sheet when it is necessary to bring a fresh portion of carbon into typing position and to insert a new carbon paper assembly.

Still a further object of the invention is to afford an arrangement whereby a carrier with carbon paper wound thereon can be easily attached to a permanent holding sheet without the necessity of any metal parts or fastening devices by means of an interlocking or other suitable retaining connection between the holding sheet and the carbon paper assembly, affording a quickly detachable relationship between these parts.

An additional purpose of the invention is to afford a construction of holding sheet that is practical, efficient, durable, and which enables securely attaching or removing a carbon paper assembly quickly and easily, without soiling the fingers by contact with the carbon on the sheet.

To these and other ends, the invention consists in the construction and arrangement of parts that will appear clearly from the following description when read in conjunction with the accompanying drawings, the novel features being pointed out in the claims following the specification.

2

In the drawings:

Fig. 1 is a plan view of a structure made in accordance with a preferred embodiment of the invention, showing the carbon paper in position for insertion between sheets of record paper;

Fig. 2 is a similar view looking at the opposite side of the holding sheet;

Fig. 3 is a plan view of the carbon paper and carrier plate removed from the holding sheet;

Fig. 4 is a plan view of the carrier plate with the carbon paper unrolled and showing its one end fastened to the carrier;

Fig. 5 is a sectional view on the line 5—5 of Fig. 1, and

Fig. 6 is an end elevation of the carbon paper and carrier plate.

Various structures have been used for attaching carbon paper in manifolding typewriters and the prior devices possess various disadvantages which are overcome by the present invention. It has been proposed to fasten a sheet of carbon paper to each supporting bar of the typewriter, and this was found objectionable because a bar must be removed each time a carbon is replaced.

Another disadvantage lies in the excessive waste each time a carbon is replaced because of the length of carbon paper constituting the connecting portion between the typing area and the supporting bar.

Another proposed structure employs a carbon sheet attached to a leader sheet of plain paper which in turn is secured to the supporting bar. This is also open to the objection of excessive waste of carbon paper as well as the difficulty and loss of time involved in removing the leader sheet from a supporting bar each time a carbon is to be replaced.

There has also been employed a flat rolled pack of carbon paper secured to a supporting bar, but this has the objection that the carbon paper pack must be removed from the supporting bar and repositioned each time that the carbon paper is unfolded to expose a fresh portion, or when the carbon pack is renewed, entailing considerable loss of time.

Another prior structure utilizes a series of sheets of carbon paper attached to a common leader sheet which in turn is secured to a supporting bar, and this structure is also open to the objection of excessive waste, because a certain portion of each carbon sheet serves as a connection from the typing portion to the leader sheet and cannot be used. In addition, the leader sheet must be removed from the supporting bar when the carbon sheets are used, and in order to insert a new

carbon pack, a new leader sheet must be attached to the supporting bar. This structure is open to a further objection that when tearing off a used sheet of carbon and positioning a fresh carbon for operation, the operator's fingers necessarily come in contact with the carbon coating and it is difficult to prevent soiling the hands.

All the above mentioned disadvantages are overcome with the present invention which is the first instance of a structure in which a leader or holding sheet is permanently fastened to a supporting bar of a manifolding typewriter, and is constructed so as to hold a supply of carbon paper wound on a carrier or plate, the carbon paper assembly being detachably secured to the holding sheet for operation in a typewriter in the same manner and with the same degree of efficiency as if the carbon sheet were attached directly to the supporting bar. This arrangement permits a carbon paper assembly to be easily and quickly removed from a holding sheet to position another portion of the carbon paper for operation or to permit the insertion of a new carrier with a fresh supply of carbon paper.

With such a structure, a substantial supply of carbon paper can be wound on a carrier and unfolded as fresh portions are required by temporarily removing the carrier from the holding sheet, with no waste of carbon paper except the small portion at the end of the roll which attaches to the carrier plate. A material saving in time results because it is unnecessary to remove the supporting bars from the typewriter at any time after the holding sheets are once attached, and proper position of each carbon sheet is assured by the connection between the holding sheet and the carbon assembly.

This result may be accomplished in a variety of ways, and in the construction disclosed, which is intended merely as illustrative of one practical embodiment, there is provided a flexible holding sheet including a relatively thin connecting portion 1 consisting of a single thickness of fabric or other suitable material which is permanently secured to a supporting bar 2, constituting a conventional part of a manifolding typewriter, as well known in the art. The holding sheet may be permanently fastened to the supporting bar 2 in any convenient way as by folding it around one edge of the supporting bar and securing it in position by spring clips 3, and when once attached, the holding sheet remains permanently connected to the supporting bar 2. When the supporting bar is once positioned in the carbon paper carriage with the holding sheet secured, it is not again removed or disturbed, and the carbon sheet can be adjusted in relation to the holding sheet to expose a fresh portion of carbon whenever required, or a new carbon paper assembly can be attached to the holding sheet, without removing the latter from the supporting bar 2.

The holding sheet also includes a supporting portion 4 preferably thicker and stiffer than the connecting portion 1 and formed of several thicknesses of material by folding one thickness around the lower part of the first mentioned thickness and cementing it thereto on opposite sides, so that the connecting portion 1 consists of a single ply and the supporting portion 4 consists of three plies of the same material, thus according to the supporting portion sufficient body and stiffness to maintain the carbon paper carrier plate in proper position.

The carbon paper assembly preferably consists of a sheet of carbon paper 5 having one end

adhesively or otherwise suitably attached to the carrier plate, as illustrated at 6, the carbon paper being wound around the carrier plate with the carbon surface facing inwardly, as illustrated in Fig. 5, so as to protect the fingers from contact with the carbon. The carrier plate is indicated at 7 and is preferably constructed of thin, stiff fiberboard, cardboard, or like material suitable for the purpose, and relatively wide to enable 10 winding a substantial quantity of carbon paper thereon. For practical purposes, the carrier plate is about four inches in width, and lies flatwise on the stiff supporting portion of the holding sheet, being removably secured thereto in any practical manner, with the free end of the carbon paper extending beyond the holding sheet for positioning between sheets of record paper, as usual in a manifold typing operation.

The detachable connection between the carbon paper assembly and the holding sheet may be of any suitable form, and in order to accomplish this in the embodiment illustrated, the holding sheet is provided with two spaced parallel slots 8 extending transversely of the holding sheet and spaced apart a distance between the outermost edges of the slots somewhat less than the width of the carrier plate 7 so that when opposite edges of the carrier plate 7 are inserted through the slots 8, the body of the carrier plate 30 with the carbon paper rolled thereon will be positioned on one side of the holding sheet while the edges of the carrier plate extend through the slots 8 and engage the opposite side of the holding sheet.

To enable inserting the carrier plate and carbon paper through the slots 8, the slots are slightly greater in length than the opposite side edges of the carrier plate. The carbon paper has a width the same as or less than the length of the opposite edges of the carrier plate 7, and somewhat less than the length of the slots 8, whereby the carbon paper assembly can be readily inserted through the slots 8. The carrier plate is positioned on the holding sheet by first inserting 45 the free end of the carbon sheet 5 through the lower slot 8, with the carbon surface uppermost, and then inserting the opposite side edges of the carrier plate through the slots 8 while flexing slightly the ends of the carrier plate transversely with the thumb and fingers, until they enter the slots 8 and assume the position illustrated in Figs. 1 and 2.

Some means must be provided for holding the carrier plate and carbon paper in operative position on the holding sheet and engaged with the slots 8, and this is accomplished in the structure shown by locking portions 9 arranged centrally of the carrier plate 7 and extending endwise beyond the ends of slots 8 when the carrier plate is positioned. The locking portions 9 are of slightly less width than the distance between the innermost edges of the slots 8 and serve to hold the carrier plate securely engaged with the slots 8. To effect removal of the carrier plate from the slots, the edges of the plate 7 are engaged and the plate flexed transversely until the opposite side edges are disengaged from the slots, and this operation is facilitated by cutting away the side edges of the holding sheet at 10 to afford recesses 60 which permit readily taking hold of the underside of the carrier plate at its ends, when it is positioned on the holding sheet. If preferred, the upper slot 8 can be omitted, the carbon paper extending through the lower slot, and the carrier

plate held removably on the holding sheet by any suitable means.

In operation, to attach a carbon paper assembly, the carbon paper is unwound from the carrier plate to expose a free end of sufficient length for a typing operation and the free end is inserted through the lower slot 8 of the holding sheet. At the same time, the ends of the carrier plate 7 are held and flexed while holding the carrier plate against the holding sheet and inserting the opposite side edges of the carrier plate and carbon paper wound thereon into the slots 8. The locking portions 9 engage the front of the holding sheet between and beyond the slots 8, as shown in Fig. 1, whereas the opposite side edges of the carrier plate extend through the slots and engage the opposite face of the holding sheet, as shown in Fig. 2. When the exposed portion of the carbon paper has been used and is no longer of service, the carrier plate is flexed and removed from the holding sheet in the manner already described, and the carbon paper unwound from the carrier plate to bring a fresh portion into operative position, after which the carrier plate is again attached to the holding sheet in interlocking engagement with the slots 8. The used portion of the carbon sheet is torn off and the carbon paper is ready for another operation. This procedure is continued until the entire length of carbon paper wound on the plate 7 is used, whereupon it is removed from the holding sheet and another carrier plate with a fresh supply of carbon paper is inserted into the slots and supported on the holding sheet.

With this construction, it is possible for the operator to bring a fresh supply of carbon paper into operative position, or to insert a new carbon paper assembly without removing or disturbing in any way the supporting bar, so that after the holding sheet is once positioned properly on the typewriter supporting bar, accurate and proper positioning of the carbon sheet is automatically assured and no further adjustment is required. The carbon paper assembly can be quickly secured to a holding sheet and easily removed when necessary to bring a fresh portion of carbon into operative position or to insert a new carbon paper assembly, and this can be done without contacting the carbon surface of the paper so that soiling the fingers is prevented.

While the invention has been described with reference to the particular structural embodiment shown, it is not confined to the details herein disclosed, and this application is intended to cover such modifications or changes as may come within the purposes of the improvements or the scope of the following claims.

I claim:

1. The combination with a flexible holding sheet that is permanently attachable to a supporting bar of a manifolding typewriter, of a carbon paper carrier detachably and interlockingly connected to said holding sheet, and a length of carbon paper fastened at one end to the carrier and wound continuously therearound affording a multiplicity of superposed thicknesses and a free end extending beyond said holding sheet, the holding sheet provided with means interlockingly engaging the carbon paper carrier and permitting removal of the carbon paper and carrier without disturbing the position of the holding sheet on the supporting bar, the carbon paper carrier being retained on the holding sheet by the interlocking relation between the holding sheet and carbon paper carrier.

2. The combination with a flexible holding sheet that is permanently attachable to a supporting bar of a manifolding typewriter, of a carbon paper carrier consisting of a plate detachably and interlockingly mounted on said holding sheet, and a length of carbon paper fastened at one end to the carrier plate and wound continuously therearound affording a multiplicity of superposed thicknesses and a free end extending beyond said holding sheet, the holding sheet provided with means interlockingly engaging the carbon paper carrier and permitting removal of the carbon paper and carrier without disturbing the position of the holding sheet on the supporting bar, the carbon paper carrier being retained on the holding sheet by the interlocking relation between the holding sheet and carbon paper carrier.

3. The combination with a flexible holding sheet that is permanently attachable to a supporting bar of a manifolding typewriter, of a relatively wide carrier plate of stiff material detachably connected to said sheet and quickly removable therefrom, the carrier plate having interlocking means engaging the holding sheet and permitting removal of the carrier plate and carbon paper without disturbing the position of the holding sheet on the supporting bar, and a length of carbon paper fastened at one end to the carrier plate and wound continuously therearound affording a multiplicity of superposed thicknesses and a free end extending beyond said holding sheet.

4. The combination with a flexible holding sheet that is permanently attachable to a supporting bar of a manifolding typewriter, of a carbon paper carrier of stiff material removably associated with said sheet and quickly detachable therefrom, means on the carrier having interlocking engagement with the holding sheet and permitting removal of the carrier and carbon paper without disturbing the position of the holding sheet on the supporting bar, and a length of carbon paper fastened at one end to the carrier and continuously folded therearound with a free end extending beyond said holding sheet.

5. The combination with a flexible holding sheet that is permanently attachable to a supporting bar of a manifolding typewriter, said holding sheet having spaced parallel slots extending transversely thereof, of a carbon paper carrier consisting of a stiff plate having a width somewhat greater than the distance between the outermost edges of said slots and side edges of less length than said slots, said carrier being provided with locking portions at its ends extending beyond said slots and of slightly less width than the distance between the innermost edges of the slots, and a length of carbon paper having one end attached to the carrier and wound continuously therearound, the carbon paper being of less width than the length of the slots and the locking portions of the carrier being positionable on one side of said holding sheet while opposite edges of the carrier and carbon paper assembly extend through said slots to the opposite side of said holding sheet and a free end of the carbon paper extends beyond the holding sheet, permitting removal of the carrier plate and carbon paper without disturbing the position of the holding sheet on the supporting bar.

6. The combination with a flexible holding sheet that is permanently attachable to a supporting bar of a manifolding typewriter, the hold-

ing sheet including a relatively thin connecting portion and a relatively thicker supporting portion, said supporting portion of the holding sheet having a pair of parallel spaced slots extending transversely thereof, of a carrier consisting of a stiff plate having a width greater than the distance between the outermost edges of said slots and detachably positionable through the slots, said carrier having opposite side edges of less length than the slots and central locking portions at its ends extending beyond the ends of the slots and of less width than the distance between the innermost edges of the slots, and a length of carbon paper having one end fastened to the carrier and wound continuously thereon, the carbon paper being of less width than the length of said slots and the opposite side edges of the carrier and the carbon paper assembly being insertable through said slots to one side of the holding sheet while said locking portions engage the opposite side of the holding sheet and a free end of the carbon paper extends through one of the slots beyond said holding sheet, permitting removal of the carrier plate and carbon paper without disturbing the position of the holding sheet on the supporting bar.

7. The combination with a flexible holding sheet that is permanently attachable to a supporting bar of a manifolding typewriter, said holding sheet having a transverse slot near its lower edge, of a carbon paper carrier consisting of a stiff plate removably associated with said holding sheet and quickly detachable therefrom, and a length of carbon paper fastened at one end to the carrier plate and wound continuously thereon affording a multiplicity of thicknesses and a free end extending through said slot beyond the holding sheet, the holding sheet provided with means engaging the carrier and permitting removal of the carbon paper and carrier without disturbing the position of the holding sheet on the supporting bar.

8. The combination with a flexible holding sheet that is permanently attachable to a supporting bar of a manifolding typewriter, the holding sheet including a connecting portion comprising a single thickness of material and a supporting portion comprising another thickness of material folded around both sides of said first thickness and cemented on both sides thereto affording a triple thickness of material, said supporting portion of the holding sheet having a pair of parallel spaced slots extending transversely thereof, of a carrier consisting of a stiff plate having a width greater than the distance between the outermost edges of said slots and detachably positionable through the slots, said carrier having opposite side edges of less length than the slots and central locking portions at its ends extending beyond the ends of the slots and of less width than the distance between the innermost edges of the slots, and a length of carbon paper having one end fastened to the carrier and wound continuously thereon, the carbon paper being of less width than the length of said slots and the opposite side edges of the carrier and the carbon paper assembly being insertable through said slots to one side of the holding sheet while said locking portions engage the opposite side of the holding sheet and a free end of the carbon paper extends through one of the slots beyond said holding sheet, permitting removal of the carrier plate and carbon paper without dis-

turbing the position of the holding sheet on the supporting bar.

9. The combination with a flexible holding sheet that is permanently attachable to a supporting bar of a manifolding typewriter, a carbon paper carrier and a length of carbon paper wound continuously thereon affording a multiplicity of superposed thicknesses and a free end extending beyond the holding sheet, of interlocking retaining means located between the side edges of the holding sheet, said retaining means acting to receive and interlock with the carbon paper carrier to secure it to the holding sheet and permitting removal of the carbon paper and carrier without disturbing the position of the holding sheet on the supporting bar.

10. The combination with a flexible holding sheet that is permanently attachable to a supporting bar of a manifolding typewriter, of a flexible carbon paper carrier extending across the width of the holding sheet and detachably and interlockingly connected to said holding sheet, the holding sheet being provided with means interlockingly engaging the carbon paper carrier 15 at its ends and permitting removal of the carbon paper and carrier without disturbing the position of the holding sheet on the supporting bar, the carbon paper carrier being retained on the holding sheet by the interlocking relation between the 20 engaging means and carbon paper carrier and attached thereto by a relative flexing of one of said parts in the direction of the plane of the holding sheet.

11. The combination with a flexible holding sheet that is permanently attachable to a supporting bar of a manifolding typewriter, and a carbon paper pack comprising a length of carbon paper wound continuously and affording a multiplicity of superposed thicknesses and a free end extending beyond the holding sheet, of retaining means extending through the carbon paper pack from one end thereof to the other and detachably and interlockingly connected to the holding sheet for permitting removal of the carbon paper pack without disturbing the position of the holding sheet on the supporting bar, the flexible holding sheet being provided with means interlockingly and detachably engaging said retaining means.

12. The combination with a flexible holding sheet that is permanently attachable to a supporting bar of a manifolding typewriter and a carbon paper pack, of a flexible support for the carbon paper pack, said support being detachably mounted on the flexible holding sheet, and mutually engaging and interlocking instrumentalities on said support and flexible holding sheet acting to hold the carbon paper support removably interlocked with the holding sheet, the carbon paper support being attached to the flexible sheet by a flexing of one of said parts in the direction of the plane of the holding sheet.
